BUTTONHOLE SPACER

Adam A. Weingartner, North Bergen, N. J.

Application June 1, 1950, Serial No. 165,451

9 Claims. (Cl. 112—75)

1

My invention relates generally to buttonhole spacers and specifically to buttonhole spacers which, with a single setting, will determine a plurality of spacings.

It is among the objects of my invention to provide for the accurate placement of buttonholes on items wherein a plurality of successive holes are to be made and spaced equidistant from each other.

It is a further object of my invention to provide a means for quickly determining the position of a plurality of buttonholes comprising a series.

It is yet a further object of my invention to provide an adjustable variable means for placing a variable number of equally spaced buttons in relationship corresponding to the size of the garment to which they are attached.

It is among the further objects of my invention to provide a buttonhole spacer that is simple in form, easy to use, relatively inexpensive, and durable.

These objects and advantages, may be achieved by the device illustrated in the drawings, in which:

Figure 1 is a top view showing the buttonhole spacer disposed in operable relationship to a buttonhole machine, and an item symbolical of a garment to which buttonholes are to be applied; and

Figure 2 is a side view of the buttonhole spacer. Referring now to the drawings in detail, my buttonhole spacer has a bar or support 11 which serves as a mounting for the several indicators or positioning means. This support 11 is attached to the machine table 12 by a bracket 13 at one end, and another bracket 14 at an intermediate point. Mounted on the support 11, there is an index 15. This index is attached to the support 11 by a pivot pin 16. One end of the index 15 has a down-turned end or pointer 17. The other end, beyond the pivot pin 16 has an extended portion 18. This extended portion 18 has a plurality of holes 19 disposed in a series.

At the opposite end of the support 11, there is another index 20. This index 20 is also attached to the support 11 by a pivot pin 21. The tip of the index 20 is provided with a point 22 so that it may be precisely lined up with a point on a garment. Between the point 22 and the pivot pin 21, there is another pivot pin 23 mounted on the index 20 which serves as a mounting for a connector 24. The connector 24 is a rod or bar which is attached at one end as aforesaid, and at the other end, is attached to the index 15 by a pivot pin 25 inserted in one of the holes 19. The pivot pin 23 is threaded so that it will engage the threads in the hole which it enters in the index 20. By tightening the pivot pin 23, the index 20 may be locked at any chosen position. Adjacent to the point where the pivot pin 23 attaches the connector 24 to the index

20, there is a series of holes 26 in the connector 24. These holes 26 enable the bar to be adjusted to accommodate garments of varying sizes beyond the ordinary range of adjustment. The holes 19 on the other hand, are positioned so as to increase or decrease the ratio of movement of the indexes when they are moved with respect to each other. Thus, one of the holes 19 may be the setting by which an operator can gauge the position of the successive buttonholes in a series of 8, while the next hole will gauge the position of successive buttonholes in a series of 7, et cetera.

Now for the manner of use and operation of my buttonhole spacer, the operator makes the first buttonhole 27 in the garment which is symbolically illustrated by the buttonhole strip 28. The strip is then moved on the table and the indexes are adjusted so that the index 22 coincides with the point where it is desired that the last buttonhole shall fall, and the pointer 17 lies over the first buttonhole 27 as shown in Figure 1. The second buttonhole 29 will then fall at the point of the needle 30. To keep the pointer 17 as a gauge point for successive buttonholes, the pivot pin 23, which is in reality also a set screw, is tightened. Thus having completed the second buttonhole 29, that buttonhole 29 is moved into coincidence with the pointer 17 and the correct position for the next buttonhole will automatically lie under the needle 30. This is brought about because the distance from the needle 30 to the point 22 is always the same multiple of the distance from the needle 30 to the pointer 17 regardless of where the point 17 is moved to. Depending on the hole 19 selected, distance 32 will, for example, if six buttonholes are to be made, always be four times greater than distance 31. And if for example, seven buttonholes are to be made, the connector 24 is advanced from the "six" buttonhole hole 19, to the next hole 19 which is the "seven" buttonhole hole. Automatically, the distance 32 delineated by the point 22 and the needle 30 will be five times the distance 31 measured by the pointer 17 and the needle 30.

The operator then continues to move each buttonhole when completed to the pointer 17 and the correct position of the next buttonhole will fall at the needle. This operation is continued until the requisite number of buttonholes in the series has been made.

The foregoing description is intended merely as illustrative of one embodiment of my invention, for many changes in the construction, selection and arrangement of the various elements of my device may be made within the scope of the claims, without departing from the spirit of the invention.

I claim:

1. A buttonhole spacer comprising a support, a pair of indexes pivotally attached to the support,

a connector attached at one end to one of the indexes and at the other end to the other index at the opposite side of its pivotal connection to the support, and a plurality of means for attaching the connector to various points on one index.

2. A buttonhole spacer comprising a support, an index pivotally attached to the support and extending on one side thereof, an index pivotally attached to the support and extending on the same side as the first index but having an extended portion on the opposite side of the support, a connector pivotally attached to both the extended portion and to the other index, and a plurality of means for attaching the connector to various points on the extended portion.

3. A buttonhole spacer comprising a support, an index pivotally attached to the support and having an end constituting a reference point, another index pivotally attached to the support and having an end on the same side of the support as the first index, said end constituting a reference point, an extended portion of the said other index beyond its pivotal attachment to the support, a connector pivotally attached to the extended portion and pivotally attached to the other index on the other side of the support, whereby movement of either index will produce an opposite movement of the other index, and a plurality of means for attaching the connector to various points on the extended portion.

4. A buttonhole spacer comprising a support, an index pivotally attached to the support and having an end constituting a reference point, another index pivotally attached to the support and having an end on the same side of the support as the first index, said end constituting a reference point, an extended portion of the said other index beyond its pivotal attachment to the support, a connector pivotally attached to the extended portion and pivotally attached to the other index on the other side of the support, whereby movement of either index will produce an opposite movement of the other index, and a plurality of means for attaching the connector to various points on the extended portion.

5. A buttonhole spacer comprising in combination with a sewing machine, a support, a pair of indexes pivotally attached to the support, a connector attached at one end to one of the indexes and at the other end to the other index at the opposite side of its pivotal connection to the support, and the said assemblage positioned with respect to the needle of the sewing machine so that the distance between the first index and the needle is always the same multiple of the distance between the other index and the needle.

6. A buttonhole spacer comprising in combination with a sewing machine, a support, an index pivotally attached to the support and extending on one side thereof, an index pivotally attached to the support and extending on the same side as the first index but having an extended portion on the opposite side of the support, a connector pivotally attached to both the extended portion and to the other index, and the said assemblage positioned with respect to the needle of the sewing machine so that the distance between the first index and the needle is always the same multiple of the distance between the other index and the needle.

7. A buttonhole spacer comprising in combination with a sewing machine, a support, an index pivotally attached to the support and having an end constituting a reference point, another index pivotally attached to the support and having an

end on the same side of the support as the first index, said end constituting a reference point, an extended portion of the said other index beyond its pivotal attachment to the support, a connector pivotally attached to the extended portion and pivotally attached to the other index on the other side of the support, whereby movement of either index will produce an opposite movement of the other index, and the said assemblage positioned with respect to the needle of the sewing machine so that the distance between the first index and the needle is always the same multiple of the distance between the other index and the needle.

8. A buttonhole spacer comprising in combination with a sewing machine, a support, an index pivotally attached to the support and having an end constituting a reference point, another index pivotally attached to the support and having an end on the same side of the support as the first index, said end constituting a reference point, an extended portion of the said other index beyond its pivotal attachment to the support, a connector pivotally attached to the extended portion and pivotally attached to the other index on the other side of the support, whereby movement of either index will produce an opposite movement of the other index, and a plurality of means for attaching the connector to various points on the extended portion, and the said assemblage positioned with respect to the needle of the sewing machine so that the distance between the first index and the needle is always the same multiple of the distance between the other index and the needle.

9. A buttonhole spacer comprising a support, a first index pivotally attached at one end to the support and having its other end constituting a reference point adjustable to the location of the last buttonhole of a series to be applied to a garment; a second index pivotally attached to the support, having one end constituting a reference point adjustable to the first buttonhole of a series and extending on the same side of the support as the first index; and said second index having its other end extending beyond the point of pivotal attachment to the support, a connector having one end pivotally attached to the said other end of the index and the other end of the connector pivotally attached to the first index on the other side of the support, and the said assemblage positioned with respect to the needle of a sewing machine so that the distance between the first index and the needle is always the same multiple of the distance between the first index and the needle.
